UNITED STATES PATENT OFFICE.

ROBERT S. PEELLE, OF NEW YORK, N. Y., ASSIGNOR TO THE PEELLE COMPANY, OF BROOKLYN, NEW YORK, A CORPORATION OF NEW YORK.

CONTROLLING MECHANISM FOR ELEVATOR DOORS.

1,410,272.

Specification of Letters Patent. Patented Mar. 21, 1922.

Application filed March 5, 1920. Serial No. 363,531.

To all whom it may concern:

Be it known that I, ROBERT S. PEELLE, a citizen of the United States, residing at Hollis, in the borough of Queens, city of New York, county of Queens and State of New York, have invented certain new and useful Improvements in Controlling Mechanisms for Elevator Doors, of which the following is a specification, reference being had 10 therein to the accompanying drawings, which form a part thereof.

My invention relates to controlling mechanisms for elevator doors, and more particularly to such a mechanism of the full automatic type, the term "full automatic" in this art referring to a door which may be both opened and closed without the application of manual power thereto.

In an elevator door made in accordance 20 with my invention, I provide, in conjunction with the actuating mechanism for opening and closing the door, means whereby the motive power for the actuating mechanism may be so disconnected therefrom as to 25 permit the manual opening and closing of any door in a shaft independently of said motive power. Considering the invention more specifically, I employ an electric motor controllable from within an elevator car, 30 said motor being connected through a clutch mechanism to a winch drum about which is passed a cable operatively connected with each door in a shaft, in a manner to permit the opening of any door by said controller, 35 said clutch mechanism being adapted to be released by means of a pull cord extending through the entire height of the elevator shaft adjacent to a car, or other means accessible from a car when it is at any floor. 40 The actuating means is so constructed that, when the clutch mechanism is operative to transmit power to the drum, the circuit to the motor will be automatically interrupted when the door has attained its 45 fully opened or fully closed position, said clutch mechanism being capable of actuation, however, to disconnect said winch drum from the motor and thus arrest movement of the door at any time in the event of an emergency, so as to impart an additional factor 50 of safety to doors of this character.

The actuating mechanism also embodies a brake structure normally operative upon the motor, and through said clutch mechanism upon the drum, means being provided

for releasing said brake mechanism when power is applied for the purpose of either opening or closing a door.

I also provide means whereby the cable payed out when closing a door, will be automatically taken up by a movable weight adapted to actuate the circuit controlling mechanism and the main power for actuating the car, this mechanism being operative in the same manner whether a door is 65 opened by means of a motor, or manually after the clutch mechanism is released.

The invention consists primarily in a controlling mechanism for elevator doors embodying therein a plurality of vertically 70 sliding doors in a shaft, a source of power, operative connections between said source of power and each door in a shaft, a controller within a car whereby said source of power may be applied to either open or close a 75 door, and means whereby said source of power may be disconnected from said connections to permit the manual opening or closing of any door; and in such other novel features of construction and combination 80 of parts as are hereinafter set forth and described, and more particularly pointed out in the claims hereto appended.

Referring to the drawings,

Fig. 1 is a view showing a portion of an 85 elevator shaft showing two doors therein and a controlling mechanism therefor embodying my invention, the showing being largely diagrammatic;

Fig. 2 is a side view of the winch drum 90 and the clutch mechanism for controlling the application of power thereto;

Fig. 3 is an end view thereof;

Fig. 4 is a detail view of the brake mechanism for preventing excess movement of the 95 motor in opening and closing the door; and

Fig. 5 is a diagrammatic view of the wiring of the controlling mechanism.

Like letters refer to like parts throughout the several views.

In the embodiment of my invention shown in the drawings, I have indicated at A a portion of an elevator shaft having mounted therein two door structures of a type in which the sections, in opening and closing the doors, have simultaneous movement in opposite directions in the same vertical plane. The construction of each of the doors shown is the same as the other, and duplicate reference letters are therefore used in conjunc- 105 110

tion therewith. Each of the doors comprises an upper section *a* and a lower section *b* connected by the cable or other flexible connection *c* passing over the pulleys *c'*.
 5 The lower section *b* is provided with a hanger bar *b'* projecting beyond each side of the section *b*. The detailed construction of the doors is immaterial to the present invention, and is therefore not shown in the drawings or herein described.

10 The section *b*, in the type of door shown, overbalances the section *a* so that when the latch mechanism of the door is released, which mechanism is shown conventionally at *d*, there is a normal tendency of the door to open automatically.

15 In connection with said doors, I provide means whereby any door in a shaft at the landing close by which, a car is at rest, may be opened or closed from a source of power controllable from within the car, means being provided whereby said source of power may be made inoperative as to said doors to either permit the manual opening or closing 20 of a door or in an emergency prevent the forceful closing of a door, and thus avoid possibility of accidents.

25 In the form of the invention shown, the source of power consists of a reversible electric motor *e* actuating a worm gear shaft *e'* co-operating with a worm gear *f*, carried by a shaft *f'*. Idly mounted upon the shaft *f'* is a winch drum *f''*, power being applied to said drum through the co-operating clutch 30 members *f³* and *f⁴*, one of which is carried by said drum and the other of which is splined upon the shaft *f'*. Mounted adjacent the clutch mechanism *f³—f⁴* is a bell 35 crank lever, one arm *f⁵* of which is forked as shown and provided with pins *f⁶* projecting within a peripheral groove in the clutch member *f⁴*.

40 The other arm *f⁷* of said bell crank lever has connected therewith a pull cord *f⁸* extending vertically through the shaft adjacent all of the doors thereof, so that the clutch members *f³* and *f⁴* may be disconnected through the medium of said bell crank lever from adjacent any door in a shaft, and 45 thus disconnect the drum *f''* from the shaft *f'* and permit the said drum to rotate freely upon said shaft.

50 The clutch members *f³* and *f⁴* are normally maintained in engagement with each other by the spring *f⁹*.

55 Extending about the winch drum *f''* is a flexible strip, cable, or other connection *g* having branches *g'* and *g''* passing about the pulleys *g³* and *g⁴* respectively and operatively connected with each of the doors in a shaft by being passed through an opening in the hanger bar *b'* in which said extension cables *g'* and *g''* are free to slide. This construction is to permit the opening of any door in a shaft upon the actuation of the mo-

tor *e*, the strips *g'* and *g''* being capable of movement with a door to be opened and of movement independently of all the other doors in a shaft which remain closed. The extensions *g'* and *g''* carry, adjacent and below each hanger bar *b'*, a block *h* adapted to normally engage said hanger bar when the door is closed, to have movement therewith as the door is opened, and to impart movement to a door during the closing operation.

70 The extensions *g'* and *g''* each have a weight, as *i*, at the lower end thereof to maintain these extensions taut.

75 After passing about the winch drum *f''*, the flexible strip or cable *g* passes to a sliding weight *j* mounted in suitable guides *j'*, said guides adjacent the bottom thereof supporting a make and break mechanism *j''* controlling the circuit to the car actuating means. This weight, by this construction, 80 moves in synchronism with any door being opened and closed, the load of the weight, however, being sustained by the winch drum *f''*, thus relieving the doors of any influence 85 from this weight.

90 In Fig. 1 of the drawings, I have shown the controlling mechanism for the car actuating circuit, merely conventionally, since the details of this construction form no part of my present invention. It is desirable, 95 however, to control the application of power to a car in accordance with the movement of a door. The weight *j* in addition to controlling the car actuating circuit, also serves to take up slack resulting from the actuation 100 of the winch drum *f''*. I have found it desirable, however, to utilize this take-up mechanism for controlling said main actuating circuit, but do not desire to make this feature of the mechanism essential to the invention considered in its broader aspects.

105 As a consequence of the mechanism above described, it is apparent that the actuation of the motor *e* is, when the clutches *f³—f⁴* are set, essential to both the opening and the 110 closing of a door in a shaft, the extent of such movements of the doors being controlled by the duration of the operation of said motor. To limit the operative effect of the motor to open or close a door to the extent required to either fully open or fully close it, I provide means adapted to act substantially simultaneously with the completion of the closing movement, and with the completion of the opening movement of the 115 door, which will interrupt the circuit to the motor *e*, thus relieving the operator from any necessity for controlling the duration of the movement of the door through the controller in the car.

120 125 This automatic circuit interrupter may be aptly described as a limit switch mechanism. In addition to thus interrupting the circuit, this limit switch mechanism has the further characteristic that when a door is either fully 130

opened or fully closed, it will prevent application of power to the motor e except to actuate the winch drum f^2 in one direction only, which direction is defined by the position of the door. As will more fully appear hereinafter, this mechanism will permit a partially opened door to be moved in either direction without requiring movement thereof to the fully opened or fully closed position.

In conjunction with the limit switch mechanism, I provide an automatically acting brake operative upon the motor e , which, upon the interruption of the circuit to the motor e , will be automatically set to prevent possible overrunning of the motor after the interruption of the circuit, this braking mechanism, however, being released substantially simultaneously with the closing of the circuit to the motor e , and remaining in this condition so long as the circuit to the motor e remains closed.

While the limit switch mechanism operates entirely independently of the controller switches in the car, the actuation of the brake mechanism above referred to is controlled by said controller switches.

In describing said limit switch mechanism, said brake mechanism and said controller mechanism, I will do so in conjunction with the circuits employed in connection with the door actuating mechanism, which circuit is indicated diagrammatically in Fig. 5.

Carried by the car B is a controller switch mechanism C consisting of a frame k having upon opposite sides thereof, similar spring contact members k' , k^2 , k^3 , k^4 , k^5 and k^6 . The contact members k' to k^6 upon one side of said frame are adapted to close the various circuits incidental to the opening of a door, while the corresponding contacts upon the other side of the frame are adapted to close the circuits for the closing of a door.

Co-operating with the two sets of contacts above referred to is a bridge contact having two contact members m — m' of electro-conductive material, one of said contact members as m being adapted to engage the positive contacts of each group k' to k^6 and the other being adapted to engage the negative contacts of said groups.

In the embodiment of the invention shown, two of the contacts, as k' and k^2 , will be electrically connected through the wires 1 and 2, to the main line wires 3 and 4 from the source of power for actuating the doors. Others of the contacts, as k^3 and k^4 , will be connected through the wires 5 and 6 with the field 7 of the motor e , while the remaining contacts k^5 and k^6 will be electrically connected through the wires 8 and 9 with the armature brushes. The corresponding contacts upon the opposite side of the members m — m' will be connected respectively by the wires 1^a and 2^a with the source of power 3

and 4, by the wires 5^a and 6^a with the field of the motor, and by the wires 8^a and 9^a with the commutator brushes, there being this difference in the wiring of the two sets of spring contacts, that while the wires 8 and 9 will be connected respectively with the brushes e' and e^2 , the wires 8^a and 9^a will be connected respectively with the brushes e^2 and e' , thus reversing the direction of flow of the current in the armature with a resultant reversal of the direction of rotation of the motor. Hence the switch mechanism C in addition to its other functions, serves as a pole changer.

The limit switch mechanism comprises two switches n and o arranged upon a suitable switch board and spaced apart a distance substantially equaling the movement of a door from the fully opened to the fully closed position, or vice versa.

The switch mechanism n comprises fixed contacts n' and n^2 forming a gap in the wire 1, which gap is adapted to be enclosed by a bridge contact n^3 carried by an oscillatory lever n^4 acted upon by a spring n^5 to normally bring the contact n^3 in electrical connection with the contacts n' and n^2 . The switch mechanism o has contacts o' and o^2 similar to the contacts n' — n^2 , a bridge contact o^3 similar to the contact n^3 and a lever o^4 and spring o^5 similar to the lever and spring n^4 — n^5 . The contacts o' and o^2 form a gap in the wire 1^a instead of in the wire 1. By this construction the circuits to both sets of contacts k' to k^6 will be automatically included in the circuit from the main line 3—4 when the working conditions about the door actuating mechanism are such as to require this condition.

The lever arms n^4 — o^4 and the parts actuated thereby are oppositely set so that while movement of one of said levers in one direction will effect the closing of the circuit, similar movement of the other lever will effect the opening of its circuit.

The flexible connection g passes through both of the lever arms n^4 — o^4 and has secured thereto, intermediate said arms, contact balls or blocks p — p' adapted respectively to co-operate with said levers upon a predetermined movement of said connection g .

The brake mechanism above referred to comprises a disc q carried by and rotatable with the shaft e' . Pivotedly mounted adjacent said disc, are brake shoes q' — q^2 , one of which, q' , has pivotally mounted thereon a bell crank lever q^3 , one arm of which is connected by means of the adjustable link q^4 with the other shoe q^2 .

Mounted adjacent the disc q is a solenoid or other electro magnet r , the core of which is pivotally connected with said bell crank lever, said core being so set that upon the energizing of the magnet r , the bell crank 130

lever q^3 will be so oscillated as to release the brake shoes q' and q^2 . Acting upon the bell crank lever q^3 is a spring r' having a normal tendency to set the brake shoes $q' - q^2$ upon the disc q .

5 The solenoid r is included, by means of the terminal wires 10-11, in the circuit to the field 7, thus causing the release of the brake mechanism with any actuation of the 10 controller switch C, irrespective of the purpose for which this switch may be used.

The operation of the herein described mechanism is substantially as follows:-

15 Assuming that the parts are in the position shown in Fig. 1 of the drawings, the various doors in a shaft will be closed, the brake shoes $q' - q^2$ being set upon the disc q through the medium of the spring r' which, acting upon the core of the solenoid r as a 20 fulcrum, will draw the brake shoe q^2 against the brake drum q through the medium of the link q^4 , the resistance encountered by the shoe q^2 reacting through the lever q^3 and link q^4 to similarly set the shoe q' , thus normally preventing rotation of the winch drum f^2 and thus serve to effectively lock all of the doors in a shaft, supplementing in this respect the individual locks d operative in connection with the several doors. The 30 locking of each door through the medium of the winch f^2 results from the fact that this winch is held against rotation, thus preventing lineal traverse of the cables g , g' and g^2 so that the blocks h carried by the cables g' and g^2 will be engaged with the hanger bars of the several doors.

Under this condition it is impossible to open any door in a shaft except from the car B, the individual locks d preventing the 40 opening of any door except that closing the opening at the floor at which the car B is standing.

Assuming that the car ascends to the doorway toward the top of Fig. 1, and it is desired to open this door, when the car is brought to rest, the lock d will be released by a suitable mechanism on the car when the type of lock shown in the drawings is used. Any other desired form of lock may be used, 50 however, in lieu of that shown, my invention not relating to the form of individual lock employed.

When it is desired to open a door by the application of power from the motor e , the 55 contact members m and m' are brought into engagement with the contacts k' to k^6 of one group of said contacts. At this time the switch mechanism n will be so set as to close the circuit through the wire 1, so that with 60 the movement of the members $m - m'$, the following results will occur simultaneously. The field 7 of the motor e will be energized, the current will pass to the motor armature, and the solenoid r will be energized to release 65 the brake shoes q' and q^2 .

When the circuit is thus closed the winch drum f^2 will be driven by the motor in a manner to pay out the strip or cable g and its branches g' and g^2 , thus permitting the door, the lock d of which has been released, 70 to open as a result of the descent of the blocks h carried by the extensions g' and g^2 adjacent the hanger bar b' of that door. The blocks h adjacent the other doors will merely recede from their respective hanger 75 bars, the doors, since the cables g' and g^2 by reason of the weights i and of the weight inherent thereto, will descend by gravity, being held in the closed position by their individual locks d .

With the paying out of the portion of the strip or cable g between the winch drum f^2 and the several doors, that portion of said strip or cable g between the winch drum and the block j will be taken up, thus simultaneously permitting the opening of a door, and raising the block j .

With the initial movement of said block j , the make and break mechanism j^2 will be automatically actuated to prevent application of power to the car, thus preventing the car leaving the floor until the door has again been closed.

With the paying out of the strip or cable g in the manner above referred to, the block j^2 will recede from the lever o^4 , thus permitting the actuation of the lever under the spring o^5 , so as to close the gap in the line 1 through the contacts o^1 , o^2 and o^3 , and include the opposite set of contacts k' to k^6 in 100 the main circuit 3-4.

With the interruption of the circuit to the motor e by the contact members $m - m'$, the brake members $q' - q^2$ will instantly set upon the drum q under the influence of the 105 spring r' , thus preventing overrunning of the motor with a resultant excess movement of the doors.

Under this condition it will be observed that both switches $n - o$ are so set as to close 110 the circuits through the wires 1 and 1^a respectively, thus permitting either set of contacts k' to k^6 to be used so that the door may be either opened or closed, as desired.

So long as the circuits are closed to effect 115 the opening of a door until the door is fully opened, the closing of the circuit through the wiring 1^a in the manner above referred to will have no influence in the functioning of the device. When the door approaches a 120 fully open position, however, the ball or block p upon the strip or cable g will engage the lever n^4 , and with the completion of the opening movement of the door, oscillate said lever in a manner to separate the contacts n^1 , n^2 and n^3 , and thus automatically open the circuits to the door actuating mechanism, independently of any action of the operator, or any movement of the contact members $m - m'$. Any movement of the 125 130

winch drum f^2 in excess of that required to fully open the door, is thus prevented.

While the opening of the door will result primarily because of the greater weight in the section b than in the section a , the speed of movement will be controlled entirely by the motor e through the winch drum f^2 , the worm gear drive of said winch drum not only serving as a speed reducing transmission, but also as a lock which will relieve the door structure from any counter-balancing effect from the weight j . Of course, it is understood that the strip or cable g is passed several times about said winch drum.

When a door is fully opened, if an operator should engage the contact members $m-m'$ with the wrong set of contacts k' to k^6 , this will have no effect on the electrical conditions, since the limit switch n will be maintained in a condition which will prevent the flow of the current from the motor e or solenoid r . Hence if it be desired to close the door, the contact members $m-m'$ must be engaged with the other set of contacts k' to k^6 to close the circuits to the two brushes $e'-e^2$, but with the opposite polarity to the solenoid r , with a resultant release of the brake shoes $q'-q^2$ and the actuation of the motor e and winch drum f^2 , but in the reverse direction.

As a result of this reversal of the direction of rotation of the winch drum f^2 , it will pay out the strip or cable g between it and the weight j , while a lifting action upon the open door will be exerted by the blocks h upon the extensions $g'-g^2$.

With the initial movement of the door, the block p will recede from the lever n^4 , thus permitting the spring n^4 to actuate said lever in a manner to again close the circuit through the wire 1.

As the door approaches the closed position, the block p' will engage the lever n^4 , and actuate said lever upon the completion of said closing movement, in a manner to interrupt the circuit through the wire 1 ^{a} and thus interrupt the various circuits to the door actuating mechanism, and automatically arrest further movement of the doors.

If, from any cause, the circuit to the motor e should be so interrupted as to prevent the application of power thereto to permit the opening or effect the closing of a door, the worm gear transmission and the brake mechanism would effectively lock all doors in a shaft. The clutch members f^3-f^4 are provided to meet such an emergency as well as to permit an instantaneous stoppage of the closing movement of a door in the event of the presence of an obstruction, such as a part of the human body.

With a loss of power to the motor e , it is merely necessary for the operator within a car to exert a downward pull upon the pull cord f^8 , thus rocking the lever f^5-f^7 in a

manner to slide the clutch member f^4 along the shaft f' until said member is disengaged from the co-operating clutch member f^3 . When said clutch members are thus disengaged, the door closing the opening where a car is at rest, may be freely opened and closed by hand. When a door has been fully closed the operator may lock same by merely releasing the cord f^8 , the spring f^9 automatically causing the re-engagement of said clutch members, so that the worm gear transmission and the brake mechanism will again become operative. This condition is only necessary when the lower door section overbalances the upper door section. This, however, is the usual condition with full automatic doors.

When closing a door by means of the motor e , continuous power is applied thereto so that even though the power required is low, injury might result if a person should interpose any portion of his body between the door sections $a-b$. In such an emergency the operator would merely have to actuate the clutch members f^3-f^4 in the manner above described, to disconnect the drum f^2 from the shaft f' , and thus instantly arrest movement of the door sections, without interrupting the circuit to said motor, and furthermore, cause an instantaneous reversal in the direction of movement of the door sections.

The weight j will take up all slack in the cable g as it is created by the winch drum f^2 , said weight, as the doors approach their closing movement, actuating the make and break mechanism j^2 in a manner to close the circuit to the car actuating mechanism and thus permit power to be applied to the car for movement in either direction.

By the foregoing it will be observed that any door in a shaft may be opened and closed by means of a single door actuating mechanism; but that when a door is opened this mechanism can be operated only in a manner to close the door; that when a door is closed it may be actuated only in a manner to open the door; and that when a door is partially opened, it may be actuated either to fully open or fully close it. It will also be observed that the automatic brake mechanism operative upon the motor e , and the power transmission mechanism connecting the motor e with the winch drum f^2 , will not only effectively prevent overrunning of the motor and of the winch drum upon the interruption of the circuit to the former, but will serve to effectively lock the doors when in the closed position and prevent the fore-mentioned opening thereof from the floor side of the door opening.

The winch drum f^2 may, however, in an emergency, be disconnected from the transmission mechanism, to permit the manual operation of a door, or prevent the appli-

cation of power thereto from the motor *e*, thus affording means whereby the doors may be instantly converted into semi-automatic doors, and thus permit an elevator to be kept in service notwithstanding electrical conditions which might prevent the use of the motor *e*.

The mechanism shown in the accompanying drawings, I have found highly satisfactory in actual use, but there may be many variations thereof securing the desired operative effects, without departing from the spirit and scope of the invention. It is, therefore, not my intention to limit the invention to the precise details of construction shown in the accompanying drawings.

Having described my invention, what I claim as new and desire to have protected by Letters Patent, is:—

1. A controlling mechanism for elevator doors embodying therein a plurality of vertically sliding doors in a shaft, a source of power, operative connections between said source of power and each door in the shaft, including therein members adapted to simultaneously engage the several doors in a shaft and to have movement with any door being opened or closed, and move independently of the doors which remain closed, a controller within a car whereby said source of power may be applied to either open or close a door, and means whereby said source of power may be disconnected from said connections to permit manual actuation of a door.

2. A controlling mechanism for elevator doors embodying therein a plurality of vertically sliding doors in a shaft, an electric motor, a winch drum, a power transmission mechanism connecting said motor and said drum including therein a clutch mechanism, means adjacent each door in the shaft whereby said clutch mechanism may be actuated to make said transmission mechanism inoperative in relation to said drum, a flexible connection passing about said winch drum and operatively connected with each door in the shaft, and a controller for the circuit to said motor arranged within a car.

3. A controlling mechanism for elevator doors embodying therein a plurality of vertically sliding doors in a shaft, an electric motor, a winch drum, a power transmission mechanism connecting said motor and said drum including therein a clutch mechanism, means adjacent each door in the shaft whereby said clutch mechanism may be actuated to make said transmission mechanism inoperative in relation to said drum, a flexible connection passing about said winch drum and operatively connected with each door in the shaft, a controller for the circuit to said motor arranged within a car, and means adapted to automatically inter-

rupt the circuit to said motor when a door has reached the fully opened, and the fully closed, position.

4. A controlling mechanism for elevator doors embodying therein a plurality of vertically sliding doors in a shaft, an electric motor, a winch drum, a power transmission mechanism connecting said motor and said drum including therein a clutch mechanism, means adjacent each door in the shaft whereby said clutch mechanism may be actuated to make said transmission mechanism inoperative in relation to said drum, a flexible connection passing about said winch drum and operatively connected with each door in the shaft, a controller for the circuit to said motor arranged within a car, means adapted to automatically interrupt the circuit to said motor when a door has reached the fully opened, and the fully closed, position, a brake mechanism, means tending to normally set said brake mechanism to prevent movement of said motor and said winch drum, and an electro magnet operative to relieve said brake mechanism, said magnet being included in a circuit from said controller, whereby said brake mechanism will be released only while the circuit to said motor is closed.

5. A controlling mechanism for elevator doors embodying therein a plurality of vertically sliding doors in a shaft, a reversible electric motor, a winch drum, a power transmission mechanism connecting said motor and said drum, including therein a clutch mechanism, means adjacent each door in the shaft, whereby said clutch mechanism may be actuated to make said transmission mechanism inoperative in relation to said drum, a flexible connection passing about said winch drum and operatively connected with each door in the shaft, a controller embodying therein a pole changing switch mechanism for the circuit to said motor, and means adapted to automatically interrupt the circuit to said motor when a door has reached the fully opened, and the fully closed, position.

6. A controlling mechanism for elevator doors embodying therein a plurality of vertically sliding doors in a shaft, a reversible electric motor, a winch drum, a power transmission mechanism connecting said motor and said drum, including therein a clutch mechanism, means adjacent each door in the shaft, whereby said clutch mechanism may be actuated to make said transmission mechanism inoperative in relation to said drum, a flexible connection passing about said winch drum and operatively connected with each door in the shaft, a controller for the circuit to said motor, embodying therein electrical contacts in circuit with the line, other electrical contacts in circuit with the motor, and movable contacts adapted respec-

- tively to close the circuits through said contacts, and means adapted to automatically interrupt the circuit to said motor when said door reaches the fully opened, and the fully closed, position.
7. A controlling mechanism for elevator doors embodying therein a plurality of vertically sliding doors in a shaft, a reversible electric motor, a winch drum, a power transmission mechanism connecting said motor and said drum, including therein a clutch mechanism, means adjacent each door in the shaft, whereby said clutch mechanism may be actuated to make said transmission mechanism inoperative in relation to said drum, a flexible connection passing about said winch drum and operatively connected with each door in the shaft, a controller for the circuit to said motor arranged within a car, a limit switch mechanism whereby the operative effect of said controller will be determined by the position of any door in the shaft, and means whereby the circuit from which power to move the car is derived, will be automatically interrupted with the actuation of said drum to open a door, and will be automatically restored upon the completion of the actuation of said drum to close the door.
- 30 8. A controlling mechanism for elevator doors embodying therein a plurality of vertically sliding doors in a shaft, a reversible electric motor, a winch drum, a power transmission mechanism connecting said motor and said drum, including therein a clutch mechanism, means adjacent each door in the shaft, whereby said clutch mechanism may be actuated to make said transmission mechanism inoperative in relation to said drum, a flexible connection passing about said winch drum and operatively connected with each door in the shaft, a controller for the circuit to said motor arranged within a car, a limit switch mechanism whereby the operative effect of said controller will be determined by the position of any door in the shaft, a make and break mechanism arranged in the circuit from which power to move the car is derived, and a sliding weight connected with the end of said flexible connection after it is passed about said drum, whereby said weight will be caused to actuate said make and break mechanism to interrupt the circuit substantially simultaneously with the initial opening movement of the door under the control of said drum and said motor, and will close said circuit substantially simultaneously with the completion of said closing movement.
- 60 9. A controlling mechanism for elevator doors embodying therein a plurality of vertically sliding doors in a shaft, an electric motor, a rotatable shaft, a worm gear transmission connecting said motor and said shaft, a winch drum idly mounted on said shaft, a clutch member carried thereby, a co-operating clutch member slidably mounted upon and rotatable with said shaft, means whereby said last named clutch member may be disengaged from its co-operating member, including means adjacent each door in the shaft, a flexible connection passing about said winch drum and operatively connected with each door in the shaft, and a controller for the circuit to said motor arranged within a car.
- 10 10. A controlling mechanism for elevator doors embodying therein a plurality of vertically sliding doors in a shaft, an electric motor, a rotatable shaft, a worm gear transmission connecting said motor and said shaft, a winch drum idly mounted on said shaft, a clutch member carried thereby, a co-operating clutch member slidably mounted upon and rotatable with said shaft, means adapted to normally engage said clutch members with each other, means whereby said last named clutch member may be disengaged from its co-operating member, including means adjacent each door in the shaft, a flexible connection passing about said winch drum and operatively connected with each door in the shaft, and a controller for the circuit to said motor arranged within a car.
- 15 11. A controlling mechanism for elevator doors embodying therein a plurality of vertically sliding doors in a shaft, an electric motor, a rotatable shaft, a worm gear transmission connecting said motor and said shaft, a winch drum idly mounted on said shaft, a clutch member carried thereby, a co-operating clutch member slidably mounted upon and rotatable with said shaft, means whereby said last named clutch member may be disengaged from its co-operating member, including means adjacent each door in the shaft, a make and break mechanism arranged in the circuit from which power to move the car is derived, a sliding weight co-operating with said make and break mechanism, a flexible connection passing about said winch drum, one end of said connection being operatively connected with each door in the shaft, and the other end thereof being connected with said weight, whereby said weight will be caused to actuate said make and break mechanism to interrupt the circuit substantially simultaneously with the initial opening movement of a door, and will close said door substantially simultaneously with the completion of the closing movement of said door, and a controller for the circuit to said motor arranged within a car.
- 20 12. A controlling mechanism for elevator doors embodying therein a plurality of vertically sliding doors in a shaft, an electric motor, a rotatable shaft, a worm gear transmission connecting said motor and said shaft,

shaft, a winch drum idly mounted on said shaft, a clutch member carried thereby, a co-operating clutch member slidably mounted upon and rotatable with said shaft, means adapted to normally engage said clutch members with each other, means whereby said last named clutch member may be disengaged from its co-operating member, including means adjacent each door in the shaft, a make and break mechanism arranged in the circuit from which power to move the car is derived, a sliding weight co-operating with said make and break mechanism, a flexible connection passing about said winch drum, one end of said connection being operatively connected with each door in the shaft, and the other end thereof being connected with said weight,

whereby said weight will be caused to actuate said make and break mechanism to 20 interrupt the circuit substantially simultaneously with the initial opening movement of a door, and will close said door substantially simultaneously with the completion of the closing movement of said door, 25 and a controller for the circuit to said motor arranged within a car.

In witness whereof I have hereunto affixed my signature, in the presence of two subscribing witnesses, this 18th day of 30 February, 1920.

ROBERT S. PEELLE.
